UNITED STATES PATENT OFFICE.

JOHN CONNELL, OF ROCHESTER, NEW YORK.

MACHINE FOR LAPING HOOPS.

SPECIFICATION forming part of Letters Patent No. 292,157, dated January 22, 1884.

Application filed April 14, 1883. (No model.)

To all whom it may concern:

Be it known that I, JOHN CONNELL, of Rochester, New York, have invented an Improved Machine for Lapping Barrel-Hoops, of 5 which the following is a specification, reference being had to the accompanying drawings.

My invention relates to an improved machine for lapping hoops for barrels, kegs, &c.; and it consists in the combination, with a reciprocating knife, of a recessed shear-block provided with a stop and guide by which the action of the knife on the hoop is controlled, and of suitable mechanism for supporting the shear-block and for imparting to the knife a 15 reciprocating motion. My invention also consists in the combination, with the above parts, of a suitable guard for the hoops, and in the combination, with a single reciprocating knife-head, of two knives and the above-mentioned 20 devices arranged and adapted to produce the proper bevels on each end of the hoop, all as hereinafter more fully described and specified.

My improved lapping-machine is represented in the accompanying drawings, in which 25 Figure 1 is a side elevation. Fig. 2 is a plan view. Fig. 3 is a front view. Fig. 4 is a vertical section on the line $x x$, Fig. 1. Fig. 5 is a plan view of the shear-blocks. Fig. 6 is a section on the line $y y$, Fig. 1. Fig. 7 is a section on the line $z z$, Fig. 1. Fig. 8 represents one of the strippers detached. Fig. 9 is an end view of the same.

In the accompanying drawings, representing my improved machine for lapping hoops 35 for barrels, kegs, &c., A is the frame of the machine; B, the reciprocating arm which carries the knife C. D is the shear-block, and E the crank-shaft by which the knife is operated. F is the guide, and G the spring-guard, 40 and H the stripper.

The frame A is formed of any suitable shape to afford at one end support for the shear block or blocks, and at the other for the pivotal attachment thereto of the reciprocating arm B. 45 In the drawings I have represented the arm as pivoted between the projecting jaws I I of the frame, being sustained therein by the pivots $a a$, which are arranged so that compensation can be made for wear. On one side of 50 the frame is attached the bracket J, which sup-

ports in suitable bearings the crank-shaft E, carrying the tight and loose pulleys K K', by which power is applied to the machine. A brace, L, ties the frame together and affords a point of attachment for the bracket near the inside bearing of the crank-shaft. A crank, c, Figs. 1 and 4, attached to the inner end of the crank-shaft, is fitted with boxes $b b$, which slide in a slot formed in the extension N of the bar B, so that the latter receives a reciprocating motion from the rotation of the crank. The slot for the boxes $b b$ is formed by bolting into the extension N a suitable cap, d. It will be observed that as the crank-shaft E rotates in the direction indicated by the arrow in Fig. 1 a quick upward or return stroke is given to the bar B, carrying the knife C, while on the downstroke, at which time the cutting operation is performed, the power is applied to the best advantage. 70

The fore or vibrating end of the arm B is guided in suitable ways, O O', attached to the frame and connected together at their upper ends. In order to provide for wear of these ways, the arrangement represented in Fig. 7 75 may be adopted, in which the slides $f f'$ are attached to a lug on the arm B by the adjusting-screws $g g'$, provided with jam-nuts.

The shear-block D is fastened to the arm A by bolts passing through a flange, h, on its lower edge, Fig. 5. It is provided with a recess, i, Fig. 5, which is tapering or wedge-shaped, as seen from above. The knife C passes up and down close to the outer or right-hand side of the shear-block in Fig. 5, and the recess is made of the same shape as is desired to be given to the hoop at the end of the lapping operation. The end of the hoop being inserted in the recess in the shear-block, shavings are removed from the side thereof by the stroke or strokes of the knife on an oblique line, until the end of the hoop arrives against the stop l at the inner end of the recess. This may be accomplished by one or more strokes of the knife, according to the adjustment given to the guide F, as hereinafter described. The flat side of the hoop toward its end is thus tapered or lapped down to the desired form, and each hoop acted on by the machine will be reduced to the same shape, the lap being 90 95 100

uniformly produced on all the hoops subjected to the operation of the machine.

The reciprocating movement of the bar A, carrying the knife C up and down close to the 5 side of the shear-block, is represented in Fig. 1 by the full and dotted lines. As the knife C has its beveled or cutting-edge set at an angle with the shear-block, the shavings are removed from the hoop by a draw or slicing 10 cut, which facilitates the lapping operation and prevents the splitting or splintering of the hoop.

In order to prevent the hoop from being carried upward by the rise of the knife, a stripper 15 per, H, is secured to the shear-block in Fig. 6. The form of the stripper is shown in Fig. 8, which represents the same as seen from the outside, and in Fig. 9, which represents it as seen from the front of the machine. The stripper 20 per may be attached directly to the top of the shear-block; but in order to provide for adjusting it vertically, I prefer to attach it by a flange to the inside of the shear-block, as shown in the drawings. In Fig. 5 the stripper 25 per is represented by dotted lines.

The guide F, which projects over the narrow end of the recess, is fastened to the reciprocating arm A and travels up and down with it. The distance between the guide F and 30 the side of the shear-block may be adjusted by placing liners or washers between its inner surface and the arm. The guide is made of a suitable beveled or curved form, so as to perform the function of preventing the introduction 35 of the hoop too far into the recess until its side has been reduced by the knife. This will be readily understood by an examination of Fig. 5. The outer edge of the end of the hoop strikes against the inner inclined 40 surface of the guide, and is by it held against the vertical side of the shear-block until it has been thinned by the knife. When the lapping operation has been completed, the end of the hoop strikes against the stop l, so 45 that each hoop is lapped or tapered on the same angle and left the same thickness at the end. The guide F also prevents a crooked hoop from turning outward too far into the path of the knife. The guide may be constructed 50 to yield slightly when the hoop is introduced into the recess.

The guard G, which is attached to the reciprocating part carrying the knife, is preferably made slightly elastic or yielding, and 55 operates to hold the hoop in the proper relation with the shear-block.

In order to provide for lapping the hoop on one end and for giving it the proper taper or bevel on the point at the other, I place 60 on the opposite side of the arm the knife C', recessed shear-block D', guide F', guard G',

and stripper H', which parts are arranged to operate in a manner similar to that already described, except that the recess in the shear-block is made of a form suitable to produce 65 the bevel on the point. I am thus enabled in a single machine to perform the operations for which it would otherwise be necessary to provide two machines. The operator introduces one end of the hoop into the recessed 70 shear-block on one side, and after the hoop has been acted on therein reverses it and subjects its other end to the knife working in connection with the other shear-block. In front of each of the shear-blocks may be 75 placed the sockets n n', Fig. 3, by which the hoop is guided into the recesses.

It is obvious that any other mode of giving the requisite reciprocating motion to the knife arm or head, carrying the knife C, may be 80 adopted.

I claim—

1. The combination of the reciprocating knife C, the recessed shear-block D, provided with the stop l, and the guide F, and suitable 85 connecting mechanism adapted to support the shear-block and to impart reciprocating motion to the knife, substantially as described.

2. The combination of the reciprocating knife C, the recessed shear-block D, provided 90 with stop l, and the guard G, and suitable connecting mechanism adapted to support the shear-block and to impart reciprocating motion to the knife, substantially as described.

3. The combination of the reciprocating 95 knife C, the recessed shear-block D, provided with stop l, guide F, and guard G, and suitable connecting mechanism adapted to support the shear-block and to impart reciprocating motion to the knife, substantially as 100 described.

4. The combination of the reciprocating knife C, the recessed shear-block D, provided with stop l, guide F, and the stripper H, and suitable connecting mechanism adapted to support 105 the shear-block and to impart reciprocating motion to the knife, substantially as described.

5. In combination with a single reciprocating knife-head, the knives CC', recessed shear-blocks D D', provided with stops l l', and the guides F F', adapted and arranged to produce the proper bevel on each end of the hoop, and suitable connecting mechanism adapted to support the shear-block and to impart reciprocating motion to the knife, substantially 110 as and for the purposes described.

JOHN CONNELL.
